DESIGN FOR A COMBINED CLOCK CASE AND LAMP

Donald R. Keppler and Paul D. Keppler,
Seattle, Wash.

Application October 23, 1936, Serial No. 65,448

Term of patent 7 years

To all whom it may concern.

Be it known that we, Donald R. Keppler and Paul D. Keppler, citizens of the United States, residing at 8112 Dallas Street, in the city of Seattle, in the county of King and State of Washington, have invented a new, original, and ornamental Design for a Combined Clock Case and Lamp, of which the following is a specification, reference being had to the accompanying drawing, forming part thereof.

We claim:

The ornamental design for a combined clock case and lamp, as shown.

DONALD R. KEPPLER.
PAUL D. KEPPLER.
